(57) **CLAIM**

The ornamental design for a watch strap as shown and described.

DESCRIPTION

FIG. 1 is a front perspective view of a watch strap showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Broken lines in the drawings depict portions of the watch strap that form no part of the claimed design.
